(57) **CLAIM**

The ornamental design for a writing instrument, as shown and described.

DESCRIPTION

FIG. 1 is a perspective view of our new design for a writing instrument;

FIG. 2 is a right side view of the writing instrument of FIG. 1, the left side view being a mirror image thereof;

FIG. 3 is a front view of the writing instrument of FIG. 1; FIG. 4 is a rear view of the writing instrument of FIG. 1; FIG. 5 is a top plan view of the writing instrument of FIG. 1;

FIG. 6 is a bottom plan view of the writing instrument of FIG. 1;

FIG. 7 is a perspective view of a second embodiment of our new design for a writing instrument;

FIG. 8 is a right side view of the writing instrument of FIG. 7, the left side view being a mirror image thereof;

FIG. 9 is a front view of the writing instrument of FIG. 7;

FIG. 10 is a rear view of the writing instrument of FIG. 7;

FIG. 11 is a top plan view of the writing instrument of FIG. 7; and,

FIG. 12 is a bottom plan view of the writing instrument of FIG. 7.

The dashed lines are for illustrative purposes only and form no part of the claimed design.
